(57) **CLAIM**

The ornamental design for a hood, as shown and described.

DESCRIPTION

FIG. 1 is a front perspective view showing a hood according to a first embodiment of my new design;

FIG. 2 is a front view thereof;

FIG. 3 is a rear view thereof;

FIG. 4 is a top view thereof;

FIG. 5 is a bottom view thereof;

FIG. 6 is a right side view thereof with the left side view thereof being a mirror image thereof;

FIG. 7 is a bottom perspective view thereof from the front, right corner; and,

FIG. 8 is a top perspective view thereof from the rear, right corner.

Applicant specifically reserves the right to pursue portions of each of the designs disclosed herein, e.g., various portions of the hood (such as any individual component in isolation, e.g., side panel, front upper panel, control panel, etc.), various sub-portions of the components thereof and/or combinations of or the interface between components or subportions thereof.

Throughout the various figures of the drawings, certain views may not be provided. The omission of a particular view is intended to convey that the element(s) depicted is/are plain and unornamented in that omitted view, or that the particular ornamental appearance in that view is simply not claimed.

The broken lines represent environment or structure of the hood and do not form a part of the claimed design.
